HIS ATTORNEY IN FACT.

INVENTOR.

UNITED STATES PATENT OFFICE.

JOHN E. SNYDER, OF SWISSVALE, PENNSYLVANIA, ASSIGNOR TO THE WESTINGHOUSE MACHINE COMPANY, A CORPORATION OF PENNSYLVANIA.

BLADING.

1,075,607.

Specification of Letters Patent. Patented Oct. 14, 1913.

Application filed March 21, 1912. Serial No. 685,225.

To all whom it may concern:

Be it known that I, JOHN E. SNYDER, a citizen of the United States, and a resident of Swissvale, in the county of Allegheny and State of Pennsylvania, have made a new and useful Invention in Blading, of which the following is a specification.

This invention relates to turbine blades and means for fastening them to a blade-holding element.

One of the objects of my invention is to provide a turbine blade which will resist the vibrations due to high rotative speed of the rotor to which they are attached.

Another object of the invention is to provide means whereby the blades may be rigidly secured to the blade-holding element.

Another object of the invention is to provide a blade, the longitudinal cross-sectional area of one part of which will be considerably greater than the remaining portion of the blade.

Other objects and advantages of the invention will be specifically described hereinbelow, it being understood that changes in form, proportion, and minor details of construction may be resorted to without departing from the spirit of the invention or sacrificing any of its advantages.

In the drawings: Figure 1 is a longitudinal sectional view through a rotor constructed in accordance with my invention. Fig. 2 is a cross-sectional view on the line 2—2 of Fig. 1. Fig. 3 is a longitudinal sectional view through one of the blades. Fig. 4 is a cross-sectional view through one of the blades; and Fig. 5 is a detail perspective view of one of the packing pieces.

Referring now to the drawings by numbers of reference, 10 designates a blade-holding element which may consist of a rotor of a turbine. The blade-holding element is illustrated as being provided with a groove 11 having under-cut portions 12 and 13. In the surface of the groove 11 is a subjacent groove 14 the width of which is less than the width of the groove 11. The grooves 11 and 14 are designed for the purpose of receiving the roots of blades 15 of which there will be a suitable number to comprise a ring, the individual blades being spaced apart by the packing pieces 16.

The detail construction of the blades is best shown in Fig. 3 in which a single blade 55 is illustrated as comprising a body portion

which is concavo-convex and the cross-sectional area of which is symmetrical for a considerable length of the blade as indicated at 17. The root end of the blade, however, is thickened for a portion of its length sufficient to enable the thickened portion 18 to extend beyond the surface of the blade-holding element to which the blade is secured. In actual practice it has been found that the blades usually break or become ruptured at approximately the point where they leave the blade-holding element and I have found that by thickening the blade for a distance from the root end sufficiently to carry the thickened portion beyond the surface of the blade-holding element, the blade is made rigid and is less liable to vibrate or become disrupted. This is in part due to the fact that the moment of inertia of the blade is increased beyond the surface of the blade-holding element, so that the blade is strengthened at the point of greatest stress, and the vibrations are absorbed throughout the entire blade length instead of at approximately one point as is common in blades now generally employed. The bottom portions or roots of the blades are provided with right-angular projections 19 which are of approximately the width of the groove 14 but of less width than the groove 11. In actual practice the blades may be introduced into the groove 11 so that the projections 19 will rest in the groove 14. The packing pieces 16 may also be placed in the groove 11 so that the bottom face of each packing piece will rest upon the upper face of a projection 19 of an adjacent blade, it being understood that the blades and packing pieces are alternately introduced into the groove 11. The packing piece 16 here illustrated is shown as being provided with an inclined face 20 and a straight face 21. The inclined face 20 of the packing piece 16 will be inserted into the under-cut portion 12 of the groove 11, the straight face 21 being spaced from but adjacent to the under-cut portion 13 of the groove 11. After the blades and packing pieces are in place they may be rigidly held by inserting compound wedges 22 which may be calked in place in the usual manner.

Having thus described my invention, what I claim is:

1. A turbine blade comprising a body portion, a considerable length of which is sym-

metrical in shape and the root portion of which is thickened for a length of the blade sufficient to permit a part of the thickened portion to extend beyond the surface of the 5 blade-holding element when the blade is in place, and a projection at the root end of the blade which extends at right angles to the body portion of the blade.

2. A turbine blade comprising a body portion, a considerable length of which is symmetrical in shape and the root portion of which is thickened for a length of the blade sufficient to permit a part of the thickened portion to extend beyond the surface of the 10 blade-holding element when the blade is in place, and a projection at the root end of the blade which extends at right angles to the body portion of the blade, said projecting

15

portion being of less width than the width of the blade.

3. In combination with a blade-holding element having a groove therein, blades in the groove and packing pieces between the blades, each blade comprising a relatively thick root portion extending beyond the 20 packing pieces, the rest of the blade being of uniform thickness from the thickened portion to the end of the blade and of less thickness than the root of the blade.

In testimony whereof, I have hereunto 25 subscribed my name this 19th day of March, 1912.

JOHN E. SNYDER.
